(57) **CLAIM**

I claim the ornamental design for a display screen or portion thereof with graphical user interface, as shown and described.

DESCRIPTION

FIG. 1 is a front view of a first embodiment of a display screen or portion thereof with graphical user interface showing my new design; and,

FIG. 2 is a front view of a second embodiment of a display screen or portion thereof with graphical user interface showing my new design.

The broken lines within the figures represent portions of the graphical user interface that form no part of the claimed design.

The broken line around the figures represents the display screen and forms no part of the claimed design.
